Conrad Harris & Paul M. Joiner, of Cincinnati, O.

Letters Patent No. 745 - Dated Dec. 11, 1855.

The Schedule referred to in these Letters Patent and making part of the same:

To all whom it may concern.

Be it known, that we, Conrad Harris, and Paul Mr Givens, both of the city of Cincinnati, county of Hamilton, State of Ohio, have invented or produced a new and useful design for Wood Parlor Stoves, and we do hereby declare the following to be a full and exact description of the same, reference being had to the annexed drawings and to the letter of reference marked thereon, to wit: Letter A, being a perspective view of the stove.

What we claim is new and desire to secure by letter patent is the design, configuration and arrangement of the several ornaments as set forth in the annexed drawings, forming a new and original design for a Wood Parlor Stove, to be known and called Parlor Gem.
